UNITED STATES PATENT OFFICE.

FRANK H. MEINERS, OF CINCINNATI, OHIO.

FLUSHING-VALVE.

1,238,425.

Specification of Letters Patent. Patented Aug. 28, 1917.

Original application filed March 27, 1916, Serial No. 86,990. Divided and this application filed December 14, 1916. Serial No. 136,901.

To all whom it may concern:

Be it known that I, FRANK H. MEINERS, a citizen of the United States, residing at Cincinnati, in the county of Hamilton and 5 State of Ohio, have invented certain new and useful Improvements in Flushing-Valves, of which the following is a specification.

My invention relates to flushing valves, 10 especially for water-closets for outdoor use or otherwise where freezing of water in the valve and connections is to be guarded against. Its object is to simplify devices of this character and to render them more reliable and less liable to derangement and 15 leakage.

My invention consists in the combination of parts and in the details of construction and arrangement of parts as will herein be 20 more fully described and claimed.

In the drawing:

Figure 1 is a plan view of a device embodying my invention;

Fig. 2 is a view partly in elevation and 25 partly in vertical section on a plane corresponding to the line 2—2 of Fig. 2, parts being broken away for lack of space;

Fig. 3 is an inverted plan view of the device with the bottom plug removed to reveal the interior construction; and 30

Fig. 4 is a cross-section of the same, on a plane corresponding to the line 4—4 of Fig. 2.

My invention, as disclosed and claimed 35 herein, was originally disclosed and claimed in my co-pending application Serial No. 86,990, filed March 27, 1916, of which this present application is a division.

As shown in the drawing and as I prefer 40 to construct my invention, the valve body 1 is in the form of a long upright cylinder with a chamber 2 in its lower end closed by a bottom plug 3 and having the pipe 4 leading into its side from the water main or 45 other source of supply of water under pressure. The upper main part 5 of the body 1 is of interior diameter less than that of the chamber 2, with its lower end part where it joins the chamber 2 interiorly threaded to 50 receive the exteriorly threaded valve-seat 6, increasing in interior diameter upwardly to form the valve-seat, and with notches 7 in its bottom to receive the spanner. Above this ring 6, the valve-plug 8 slides up and 55 down in the valve body 1, being but slightly less exterior diameter than the interior di-

ameter of the body 1, and thus guided to freely enter its lower tapered end part 8' in the valve-seat.

Leading from one side of this main part 60 of the valve-body 1, preferably just above the upper end of the valve-seat ring 6, is a side port 9, which passes up the outside of the valve-body 1 and then leads into the interior of said body 1 above the highest point 65 to which the upper end of the plug 8 will travel. From the top of the valve-body 1 leads the casing tube 10; and the stem 11 has its lower end screwed into the upper end of the valve-plug 8 and extends up through 70 the casing tube 10.

The valve-body 1 also has a small drain chamber 12 at the bottom of the side port 9, with which it communicates through a very small hole 13. From this drain chamber 75 12 there leads a drain pipe 14, which may connect with the soil pipe of the water closet, not herein shown. To drain the part of the valve-body 1 above the valve-plug 8, a small hole 13' may be provided in the 80 side, leading into the side port 9.

It will be understood that the entire valve-body 1 and its connections are buried in the ground below the frost line as indicated in Fig. 2; the casing tube 10 and the 85 stem 11 therein extending up past the surface of the ground. On the upper end of the casing tube 10 is screwed the connection head 15, having a stuffing-box 16 in its top, through which the stem 11 projects without 90 allowing leakage. The head 15 has a side extension, and to this is connected the flushing pipe 17, leading to the bowl 18. The upper end part of the stem 11 extends between the members of the fork 19 projecting 95 rearwardly from the seat 20, with a nut 21 to engage its lower side with the fork 19, and held on by a lock-nut 22, capping the upper end of the stem.

As long as the seat 20 is raised, the valve-plug 8 is wedged in its seat in the ring 6; but lowering the seat 20 raises the plug 8 as indicated by the dotted lines in Fig. 2; allowing the water under pressure to pass from the pipe 4, up past the valve-seat, 105 through the side port 9, the upper part of the body 1, the casing tube 10, connection head 15, and pipe 17, to the bowl 18. The flushing continues all the time the seat is lowered, and the plug descends when the seat 110 20 is raised, or may be so heavy as to slowly raise the seat 20 by descending slowly

against the water pressure when the weight of the person is removed from the seat. Thus, the plug may be amply heavy for cutting off the flow of water by wedging in its 5 valve-seat, and thereafter resisting the water pressure sufficiently to remain closed until raised again by depression of the seat 20. As is indicated, the valve is here made of a minimum area, so that the effect of the 10 hydraulic pressure is slight, and the taper of the plug and flaring of the valve-seat are made of such length as to enable the plug to hold securely in the valve-seat. It will be understood that the plug may be of ample 15 length to have the weight required to sufficiently overbalance the seat 20, and resist the water pressure. The valve-seat ring 16 is renewed when worn; access being had through the bottom of the chamber 2 after 20 removing the plug 3. It is, of course, necessary to excavate to reach these parts. All other parts that need to be reached, such as the stuffing box 16, are above the surface of the ground. At the same time, upon closure 25 of the valve, all parts above the frost line are well drained so that the device is not rendered inoperative during extremely cold weather.

It will be seen that the parts of my 30 proved flushing valve are few and have a very simple relation to each other; all except the packing in the stuffing box 16 may be of metal, eliminating the use of rubber or other soft material in the valve itself. 35 The ring 6 may be of such ample dimensions that the efficiency of the valve-seat will not be impaired even after very considerable wear thereon, so that excavation will not be necessary for a very considerable period of 40 time. The elimination of all springs is also a great advantage.

Having fully described my invention what I claim as new and desire to secure by Letters Patent is:

45 1. In a flushing valve, in combination with a raisable and depressible seat element, a body having a middle vertically elongated main part with straight smooth interior walls, and having an inlet passage below and 50 an outlet passage above said main part, a valve seat of interior diameter increasing upwardly, between said main part and said inlet passage, a plug fitting said interior walls of said main part and slidably up and down therein, with a downwardly tapering 55 part fitting in said valve seat, an operative connection extending through the upper part of said body from said plug to said seat element, whereby said plug and said seat element are so related that either one is raised 60 as the other is depressed, said plug being of such length and thickness that it overbalances said seat element against the pressure

of water from said inlet passage, said body also having a side port from the interior 65 of said main part immediately above said valve seat to the interior of said main part above the highest point reached by the upper end of said plug when raised.

2. In a flushing valve, in combination with 70 a raisable and depressible seat element, a body having a middle vertically elongated main part with straight smooth interior walls, and having an inlet passage below and an outlet passage above said main part, a 75 valve seat of interior diameter increasing upwardly, between said main part and said inlet passage, a plug fitting said interior walls of said main part and slidably up and down therein, with a downwardly tapering part fitting in said valve seat, an operative connection extending through the upper part of said body from said plug to said seat element, whereby said plug and said seat element are so related that either 85 one is raised as the other is depressed, said plug being of such length and thickness that it overbalances said seat element against the pressure of water from said inlet passage, said body also having a side port from the 90 interior of said main part immediately above said valve seat to the interior of said main part above the highest point reached by the upper end of said plug when raised, and having a drain outlet from the bottom of 95 said side port, and an opening from the interior of said main part to said side port immediately above the lowest point reached by the top of said plug when depressed.

3. In a flushing valve, a body having a 100 middle main part with straight smooth interior walls, an inlet passage below and an outlet passage above said main part, a valve seat of interior diameter increasing upwardly, between said main part and said 105 inlet passage, a plug fitting said interior walls of said main part and slidably up and down therein, with a downwardly tapering part fitting in said valve seat, and an operative connection extending through the upper part of said body from said plug, said body also having a side port from the interior of said main part immediately above said valve seat to the interior of said main part above the highest point reached by the 110 upper end of said plug when raised, and having a drain outlet from the bottom of said side port, and an opening from the interior of said main part to said side port immediately above the lowest point reached 115 by the top of said plug when depressed.
